(57) **CLAIM**

The ornamental design for a heated styling hairbrush as shown and described.

DESCRIPTION

The FIGURE is a front view of a heated styling hairbrush showing my new design.

The broken lines in the FIGURE show portions of the heated styling hairbrush that form no part of the claimed design. All other views of the heated styling hairbrush are not shown and form no part of the claimed design.

Any surface, or any portion of any surface, of the heated styling hairbrush not shown in the FIGURE forms no part of the claimed design.

1 Claim, 1 Drawing Sheet
